(57) **CLAIM**

The ornamental design for a totem controller having an illumination region, as shown and described.

DESCRIPTION

FIG. 1 is a front perspective view of a totem controller having an illumination region showing our design in a non-illuminated state;

FIG. 2 is a top view thereof;

FIG. 3 is a bottom view thereof;

FIG. 4 is a left side view of the totem controller having an illumination region showing our design in an illuminated state;

FIG. 5 is a right side view thereof;

FIG. 6 is a front view thereof;

FIG. 7 is a rear view thereof;

FIG. 8 is a front perspective view thereof showing the illumination region in an illuminated state in grayscale; and, FIG. 9 is a top view thereof.

The broken lines in FIGS. 1-9 depicting various components of a totem controller are included for illustrating environmental structure and are not themselves part of the design. The long-short dashed lines in FIGS. 1 and 8 indicate curvature and are not themselves part of the design.

The dash-dot radiating lines emanating from the circular element in FIGS. 4-7 and the grayscale shading of the circular element in FIGS. 9-10 both represent illumination.

1 Claim, 8 Drawing Sheets
